UNITED STATES PATENT OFFICE

170,824

THROWING DAGGER

George John Kundikoff, San Pedro, Calif.

Application March 30, 1953, Serial No. 24,247

Term of patent 14 years

(Cl. D22—3)

To all whom it may concern:

Be it known that I, George J. Kundikoff, a citizen of the United States, residing at San Pedro, State of California, have invented a new, original, and ornamental Design for a Throwing Dagger, of which the following is a specification, reference being had to the accompanying drawing, forming a part hereof.

Figure 1 is a top plan view of a throwing dagger, embodying my new design;

Figure 2 is a side elevational view of said throwing dagger; and,

Figure 3 is an end view of said throwing dagger.

I claim:

The ornamental design for a throwing dagger, as shown.

GEORGE JOHN KUNDIKOFF.
